FLAT-TOP PAPER MILK CARTON

Kaiji Negoro, La Grange, Ill., assignor to Continental Can Company, Inc., New York, N.Y., a corporation of New York

Application December 28, 1954, Serial No. 478,097

11 Claims. (Cl. 229—37)

The invention relates generally to paper receptacles and primarily seeks to provide a novel form of milk carton which can be manufactured economically and with facility from paper stock to include a flat top and flat sides permitting compact, wall to wall packing of the cartons, and also stacking thereof.

An object of the invention is to provide a carton structure of the character stated wherein the flat top closure is secured to outwardly directed body flanges, wall portions of the body being angled inwardly and upwardly toward a juncture with the body flanges so as to provide finger grip recessing beneath the flanges, and said wall portions beneath the flanges being joined at each corner of the carton by a reinforcing rib structure including a vertically disposed portion immediately beneath the respective top corner and integrally connecting the body flanges in part defining said corner.

Another object of the invention is to provide a carton structure of the character stated wherein the vertically disposed reinforcing rib portions are composed of integral portions of the body flanges folded downwardly and outwardly from said flanges.

Another object of the invention is to provide a carton structure of the character stated wherein the reinforcing rib structures at the corners of the carton top closure each include an angularly offset portion composed of integral folded portions of a finger recess providing vertical wall ring disposed immediately beneath the body flanges and joining the inwardly and upwardly angled wall portions.

Another object of the invention is to provide a carton of the character stated having a body that may be formed and folded, from a rectangular blank without slitting, notching, or otherwise cutting the blank.

Another object of the invention is to provide a carton of the character stated having a body including an outwardly turned, flat top closure supporting flange of single thickness and disposed in a single plane except at the position of a lapped seam at one of the four sides thereof and a downwardly and outwardly directed vertical and integral pleat at each corner thereof.

Another object of the invention is to provide a carton of the character stated wherein the flat top is equipped with novel tamper-proof filling and pouring port closures.

Another object of the invention is to provide a carton of the character stated wherein the pouring or dispensing port has provision for accurately controlling the outpouring of milk, permitting accurate pouring to the extent of a single drop.

Another object of the invention is to provide a carton of the character stated wherein the flat top closure is in the form of a two ply assembly, the lower or inner ply having rupturable filling and dispensing ports therein and the upper or outer ply having port closing flaps thereon each larger in area than the port it covers, the dispensing port covering flap being in the form of a tear strip and extending over the underlying body flange, about

2

the edge of said flange, over the under surface of the flange and downwardly over a body wall portion.

Another object of the invention is to provide a carton of the character stated wherein are included novel means for securing a reclosure of the tear strip after the same has been torn to expose the dispensing port and returned to its port closing and flange enveloping position after the pouring of a portion only of the milk from the carton.

A further object of the invention is to provide a top closure assembly of the character stated wherein the upper and lower plies making up the assembly are arranged with the grain of the paper in the respective plies lying in right angular relation to provide maximum strength in the assembly, and the grain of the upper ply extending lengthwise of the tear strip to facilitate tearing the strip along the lines of separation.

A still further object of the invention is to provide a novel folding pattern for a rectangular blank structure from which to form a four-sided carton body, a novel method of folding the rectangular blank to provide a tubular body having outwardly turned top closure supporting end flanges, finger recesses immediately beneath the flanges, and novel strengthening ribs at the corners and beneath the flanges.

With the above and other objects in view that will hereinafter appear, the nature of the invention will be more clearly understood by reference to the following detailed description, the appended claims and the several views illustrated in the accompanying drawings.

In the drawings:

Figure 1 is a perspective view illustrating a milk carton constructed in accordance with the invention, the condition of the filled carton prior to breaking the seal at the tear strip over the dispensing port being shown.

Figure 2 is an enlarged fragmentary perspective view showing the top portion of the carton with the tear strip torn open to expose the dispensing port, and with the carton tilted into pouring position.

Figure 3 is an enlarged fragmentary perspective view showing the top portion of the carton and illustrating the manner in which the tear strip is removably secured in place by the non-adhered flap extensions in effecting a reclosure of the carton after the tear strip has been torn to expose the dispensing port and a portion of the milk has been dispensed.

Figure 4 is an exploded perspective view illustrating the top portion of the carton body and the top closure therefor, the upper and lower plies of the top closure being shown separated one from the other.

Figure 5 is an inverted plan view of the top ply of the top closure.

Figure 6 is an inverted plan view of the lower or inner ply of the top closure.

Figure 7 is a fragmentary perspective view looking up into the lower end portion of the carton body and down onto an acceptable bottom end closure to be adhered thereto.

Figure 8 is a face view of the blank from which the carton is to be formed, looking at the outside face thereof.

Figure 9 is a view of the blank similar to Figure 8, looking at the inside face thereof.

Figure 10 is an enlarged fragmentary vertical cross section taken through the top portion of the carton across the center of the filling and dispensing ports.

Figure 11 is a sectional view similar to Figure 10, taken at right angles to Figure 10 and along a line between the filling and dispensing ports.

Figure 12 is a perspective view illustrating an alternative form of end closure which may be attached to the outwardly directed flanges of the carton body, the same comprising a simple imperforate square of paper.

Figure 13 is a view similar to Figure 12 showing an

imperforate closure of the kind illustrated in Figure 12, but including flanges to engage and be adhered to the undersurfaces of the outwardly turned flanges of the carton body.

Figure 14 is a perspective view showing another alternative closure similar to the one illustrated in Figure 12, but equipped with filler and dispensing ports, and an imperforate overcap also being shown as having flanges to engage under and be adhered to the undersurfaces of the outwardly turned flanges of the carton body.

Figure 15, is a fragmentary perspective view illustrating one corner of the tubular body at the top end thereof.

In the practical development of the invention, the improved carton or container structure is fabricated from sheet paper to comprise a tubular body square in horizontal cross section and generally designated 5, a flat top closure assembly generally designated 6, and a bottom closure generally designated 7 and which may be of any approved form.

The body is formed from the blank generally designated 8 and illustrated in detail in Figures 8 and 9. It will be apparent by reference to these figures that the blank is provided with four parallel vertical score lines 9 extending across the full width of the blank and dividing the main body into two body walls 10 arranged to oppose each other in the body tube, an intermediate body wall 11 and two semi-width body walls 12. One of the semi-width walls 12 is wider than the other to the extent of the thermo-plastic resin stripe 13 thereon for providing a seam margin. When the semi-walls 12 are joined adhesively at the coated margin 13 they together form a body wall of the same width as the opposing intermediate wall 11, and a lapped side seam 14 is provided extending up the center of the wall opposing the intermediate wall 11, as shown in Figures 4, 7 and 11.

The blank is provided with three parallel score lines 15, 16 and 17 arranged near one long edge of the blank and extending the full length thereof. The top edge of the blank and the parallel score line 15 define a flange area 18 extending the full length of the blank and having a thermo-plastic resin coating applied thereon, except in an intermediate region 15a, and at small triangular areas at the locations of the score lines 9 to which reference will be made hereinafter, which may be left uncoated. If desired the same end objective may be achieved by also applying a thermo-plastic adhesive coating to the intermediate region 15a of the flange 18 when the remainder of the flange is coated, but not applying heat and pressure thereto during the process of attaching the flanges 35 and 40 of the top to the body flange. The latter method obviates the necessity for angular registration of the top with the body during the assembly operation. The parallel score lines 15 and 16 define between them the wall areas 19 which are connected to provide a finger recess defining wall ring, and in the completed body tube this wall ring will be disposed vertically and will lie between the flange areas 18 and the wider wall areas defined between the parallel score lines 16 and 17. In the completed body tube, these wider wall areas 20 are angled upwardly and inwardly toward a juncture with the body flange areas 18.

The flange areas 18 are traversed by angularly disposed score lines 21 arranged in pairs each intersecting a vertical score line at the top edge of the blank. These score lines 21 of each pair cooperate with the score line 15 and the respective score lines 9 in defining pairs of triangular areas 22 joined at the respective score line 9. These triangular areas 22 are left free of adhesive at the outer face of the blank, as shown in Figure 8, but have the thermo-plastic adhesive applied thereon at the opposite face, as shown in Figure 9. The wall areas 19 are similarly traversed by angularly disposed score lines 23, the upper ends of which join the lower ends of the lines 21 at the points of their intersection with the score line 15.

The lower ends of the lines 23 converge and meet at the intersection of the score line 16 with the score lines 9.

Score lines 25 extend vertically between the score lines 15 and 16, each from a point of intersection of two of the lines 21 and 23 with the score line 15, two of said lines 25 being disposed above the body wall 11, and one each thereof being disposed above a semi-wall portion 12, as clearly illustrated in Figures 8 and 9. Each vertical score line 25 forms with the adjacent score line 23 and the score line 16 a triangular area 26. Two angular score lines 27 extend across the wall area 20 of the body wall 11, and one such score line 27 extends across each of the wall area portions 20 of the semi-width body walls 12, each said angled score line 27 having its upper end connecting with the respective vertical score line 25 at its intersection with the score line 16, and its lower end terminating at the intersection of the respective vertical score line 9 and the horizontal score line 17. The angled score lines 27 cooperate with the adjacent horizontal score line 16 and vertical score lines 9 in providing triangular areas 28. It will be noted by reference to Figures 8 and 9 that the triangular areas 28 are formed in the wall areas 20 of the half wall portions 12 and in the wall area 20 of the body wall 11, the wall areas 20 of the body walls 10 being rectangular in shape and devoid of such triangular areas.

An adhesive stripe 29 is provided along the bottom margin of the blank and may be utilized in adhesively attaching a suitable closure at the bottom of the body. It is to be understood that any form of bottom closure may be employed, but in this illustration the bottom closure generally designated 7 is shown as including a square body 30 and flanges 31 which may be folded upwardly to embrace and be adhesively attached to the bottom margin of the tubular body. See Figure 8.

While other forms of top closures can be employed in cooperation with the novel body tube to be formed from the blank of Figures 8 and 9, a preferred form of top closure has been disclosed and generally designated 6. This top closure comprises an upper or outer ply or thickness 32, and a lower or inner ply or thickness 33. These plies are bonded together by an adhesive, and it is to be understood that in assembling the upper and lower plies, the paper is arranged with its grain disposed in 90° angular relation in the respective plies, thereby to provide maximum strength in the top closure assembly.

Double score lines 34 define the square top of the top ply, and three flange extensions 35 are provided. Each of the three flange extensions is provided with a thermo-plastic adhesive coating 36 on the undersurface thereof to engage beneath and be adhesively attached to the undersurfaces of the body flanges comprising the adhesively coated areas 18 indicated on the blank of Figures 8 and 9. It has been noted that the undersurfaces or coated areas 18a of the body flanges are opposed to the adhesively coated top closure flanges 35. It should be understood that in the fabrication of the carton all opposing surfaces which are to be bonded may be coated with the thermo-plastic adhesive, or one only of such opposing and cooperating surfaces need be coated with the adhesive in order to bring about a satisfactory attachment or bonding of said opposing surfaces when heat and pressure are applied thereagainst.

A fourth edge of the top closure is provided with an extension 37 divided by the double score lines 38 and by two parallel score lines 39 into a panel 40 which is foldable and engageable under the remaining body flange, a wall portion 41 adapted to engage uprightly against the underlying body wall portion 19 of the wall 11 between the score lines 27 thereof, and a wall portion 42 adapted to extend part-way down over the wall portion 20 and having a central tongue or finger grip extension 43 to overlie the remainder of said wall portion 20.

Double score lines 44 traverse the top ply of the top

closure adjacent the center thereof and parallel the fourth edge having the extension 37, and two parallel tear lines of perforations 45 extend across the top and the panels 40 and 41, or in other words to the score line 39 nearest the end of the finger grip extension 43. These tear lines 45 align at the ends with angled slits 46 freeing the tongue or finger grip extension 43 beyond the score line 39 nearest the end extremity of said finger grip 43.

Whereas each flange 35 has a coating of thermoplastic adhesive 36 over the full area of its undersurface, the similar extension at the fourth edge of the blank has only a limited area adhesive coating at 47 spaced outwardly from and paralleling each tear line 45 in the manner clearly illustrated in Figure 5, thus leaving the tear strip portion between the adhesive areas 47, the panel 40 and all extensions therefrom free of adhesive. This leaves a free reclosure flap retainer 48 laterally of each side of the tear strip between the tear lines 45 and where it extends through the wall portion 41, said retainers being defined in part by the angled edges 49 opposing like angled edges 50 of the free tongue extension beginning at the outermost score line 39. See Figures 3, 4 and 5. The tear strip portion of the panel 40 not coated with adhesive registers with the uncoated region 15a on the undersurface of the body flange 18.

Double score lines 51 traverse the top ply in spaced relation to and paralleling the score lines 44 and form a hinge connection for a filler port closure flap 52 which is further defined in part by a circular or arcuate slit 53 through the top ply of the top closure. An adhesive 54 is coated on the undersurface of the top ply, the same being spaced outwardly at 55 from the tear lines 45 and extending to the thermoplastic adhesive coating 36 and 47 on the undersurfaces of the ply flanges 35 and the limited area adhesive coatings 47 on the extensions at the fourth edge of the top closure ply. This adhesive application also includes a cross strip 56 extending across between the score line sets 44 and 51. A spot of adhesive may be applied at 57 on the undersurface of the filler port closure flap 52 for attachment of a filler port plug thereto, and a similar spot of adhesive 58 may be applied to the undersurface of the tear strip for attachment of a dispensing port closing plug thereto, both of said plugs to be described hereinafter.

The lower or inner ply 33 of the top closure assembly is in the form of a square paper body having a dispensing port defined at three sides by slits 59 interrupted by an unbroken tear portion 60, and at the fourth side by slits 61 angled to form a drop pour point 62, and also interrupted by unbroken tear portions 63. The slitting 59 and 61 defines a dispensing port closing plug 64 having a spot of thermoplastic adhesive 65 applied theron and spaced inwardly from the defining slits for permanently attaching the overlying tear strip to the plug 64 so that when the tear strip is torn out the plug 64 will be removed from the inner ply to expose the dispensing port and permit pouring milk therethrough. As in the case of all other opposing and adhesively attached parts, the spot applications of adhesive 58 and 65 may be used conjointly, or either to the exclusion of the other.

The lower or inner ply of the top closure also is provided with a circular slit 66 defining a filler port and a port closure plug 67, the plug being provided with an adhesive spot 68 for cooperating with the previously described adhesive spot 57 in attaching the plug to the overlying filler flap 52. The plug 67 also is held in place by the tear point interruptions 69, and it is to be noted that the flap 52 has a greater diameter than the plug 67 so as to overlap the edges thereof and leave an annulus surrounding the port 66 beneath the filler cap. The lower or inner ply of the top closure may also have an adhesive coating 70 on the top face thereof to correspond with the adhesive on the overlying top ply surface and to cooperate therewith in adhesively uniting the upper and lower plies when heat and pressure are applied

70

thereto in the assembling of the top closure unit. The adhesive coating 70 on the top face of the inner ply terminates at the edges 71 well outwardly of the dispensing port closure plug 64, and said coating also is terminated at the circle 72 spaced well outwardly from the filling port closure plug 67. The inner ply of the closure may also be provided with a thermoplastic resin coating on the margins of its lower face at 73 to facilitate adhesion of said ply and the attached upper ply to the outwardly extending, top closure supporting flanges of the carton body, clearances in these marginal coatings 73 being provided at 74 to avoid too close proximity of the coatings to the point of the dispensing port closure 64 and to the filler port and its closure plug 67.

In making up the carton from its three component parts, namely the tube body 5 formed from the blank 8 of Figures 8 and 9, the bottom closure 7 and the top closure assembly 6, the tube is formed by folding at the several score lines 9 and adhesively attaching the semi-walls 12 along the adhesive margin 13, this union being effected, as in the case of all of the adhesively bonded opposing surfaces, by the application of heat and pressure, followed by cooling and setting. It should also be understood that in addition to the adhesive margin 13 appearing in Figure 8, the opposing marginal surface 13a on the reverse face of the opposing semi-wall 12 may be provided with a thermoplastic adhesive strip. As before stated, this practice may be followed throughout the whole carton structure, the adhesive being applied to both opposing surfaces which are to be adhesively attached, or to one such surface only.

The bottom closure 7 is secured in place by folding the flanges 31 upwardly about the marginal body wall edges at the bottom of the carton, and adhesively securing them to the outer faces of said marginal edges. The bottom closure illustrated in Figure 7 is but one acceptable example, the bottom structure, in itself forming no part of the present invention. Obviously other forms of bottom closures may be employed.

In the forming or shaping of the upper end extremity of the tubular body, the wall areas 20 are folded inwardly about the score lines 17 into upwardly and inwardly sloping or angled position. The two walls 20 above the opposing walls 10 are rectangular, as will be apparent by reference to Figures 8 and 9, and the other opposing walls 20, one above the wall 11 and the other conjointly formed by portions above the half walls 12 are trapezoidal, being reduced in area by the triangular areas 28 which during the infolding of said walls 20, fold in against the adjacent wall portions 20 and about the score lines 9 and 27 to form outwardly projecting reinforcing ribs 75. The narrow wall areas 19 are folded upwardly about the score lines 16 into upright or vertical position, and the adhesively coated flange areas 18 are folded outwardly about the score lines 15 to provide top closure supporting flanges, the adhesive bearing surfaces 18a shown in Figure 8 being disposed downwardly. As before stated, the adhesive provided on the undersurface of the plies of the top closure may be relied upon to effect the desired adhesive attachment of the top closure on the outwardly directed supporting flanges 18 of the body, or the upwardly presented surfaces 18b of said flanges may also be equipped with a thermoplastic resin coating to facilitate said part attachment.

This infolding of the body areas 20, the upward or vertical folding of the areas 19 and the outward folding of the flange areas 18 provides finger grip clearances beneath the body flanges. The inclusion of the vertical wall areas 19 not only assures the provision of finger grip clearances which are more definitely defined and efficient than those provided in prior known structures, but said wall portions 19 also add rigidity and strength to the top closure arrangement. This folding also serves to cause the adjoining triangular areas 22 to fold downwardly about the score lines 21 and 9 and to engage in face

75

to face contact with the adhesive coating 18b of the top flange surfaces between them and ultimately serving to bond them in a vertically disposed reinforcing rib 76. This provision of the vertical ribs or reinforcing pleats 76 directly at each corner of the tubular body top provides a flap top closure supporting flange of single thickness and disposed in a single plane except at the positions of the vertical ribs or corner pleats and at one intermediate portion of one side where the side seam of the tubular body is positioned.

In the folding process each triangular area 26 is folded outwardly about the score lines 25 and 16 into the vertical plane of the adjacent acute angle end extremity 77 of the upright area 19 joined therewith through the connected triangular areas 24, and to lie in face to face contact with said end extremity 77 in the vertical plane. This folding also causes the connected triangular areas 24 to fold about the score lines 9, 15 and 23 to fold into face to face contact in the provision of an angularly offset reinforcing rib portion 78 of the composite strengthening rib 75, 76, 78. This offset rib arrangement provides added strength at the corners of the top closure and yet provides for substantially uniplanar contact about the whole perimeter of the top flange, except at the extreme corners, by supporting or pressure applying devices utilized in the shaping up of the body, or in the adhesive bonding of the end closure structures thereon.

In utilizing the aforementioned pressure applying or forming devices for shaping the body, end flanges and strengthening ribs, it may be found unnecessary to score all or part of the body blank because the forming or shaping devices may force the sheet to bend along the desired lines without scoring. Inasmuch as the scored lines are merely to locate the bend lines, these terms, from a practical viewpoint, may be considered equivalents with reference to the body blank.

While the two-ply assembly top closure of Figures 1 to 6 is preferred, it is to be understood that other forms of top closures may be applied to the body structure shown in Figure 4. An example of such modification is shown in Figure 12 wherein a simple imperforate square end closure 79 is illustrated, the same being adapted for attachment by adhesion to the horizontal, outwardly directed flanges of the carton body structure illustrated in Figure 4.

Another modification of top closure is illustrated in Figure 13 wherein is shown a closure similar to that of Figure 12 but including flange extensions 80. The flanges 80 may be folded under and adhered to the downwardly directed surfaces of the outwardly turned supporting flanges illustrated in Figure 4.

In Figure 14 another modified form of top closure is illustrated. This closure takes the form of a simple top square 81 having a filling port 82 and a dispensing port 83 defined therein. An overcap 84 having a body portion 85 to cover the top square may be provided, and said overcap may include flanges 86 equipped with an adhesive at 87 for attachment under the outwardly turned flanges of the carton body illustrated in Figure 4. It may be found desirable to leave a bare space 88 in the marginal coating of the overcap in line with a finger piece extension 89 thus left free to be grasped preparatory to tearing off the overcap and exposing the ports 82 and 83.

The paper sheet from which the body blanks are cut may be received in roll form, and it is preferred that it be printed on one face with the design, indicia and colors to appear on the outside of the carton. A protective coating of varnish may be applied over the decorations and printing, and thereafter the cutting and scoring of the blanks can be carried out. The upper surface of the lower ply of the top closure may also be given a protective coating of varnish if desired, but it is to be understood that the varnish coating is not intended as a bonding adhesive and will have no effect in bonding the tear strip defined between the lines of perforations

45 when the component parts of the top closure are assembled by application of heat and pressure, or during attachment of the top closure assembly to the supporting flanges of the tubular body by similar application of heat and pressure.

It will be apparent that the attachment of the defined filler and dispensing plugs 67 and 64 by the unbroken tear points 69, 60 and 63 serves to provide tamper-proof filling and pouring port closures, said closures remaining 10 sealed until the respective filler flap and tear strip portions are lifted to expose the filling and dispensing ports, the plugs 64 and 67 being forcibly torn out by such lifting of the filling flap and the tear strip.

When the fabrication of the carton has been completed in the manner previously described, the filling and dispensing ports are temporarily closed by the slit defined, but attached, filling and dispensing port closing plugs 67 and 64. It is desirable that the interior of the carton be sprayed or flushed with hot wax. This is accomplished after swinging the filler flap 52 upwardly about the score lines 51. The upward swinging of the flap 52 ruptures the imperforate portions 69 by reason of the adhesive attachment of the plug 67 with the flap, and the pulling of the plug 67 out of the filling port 66 exposes said port and provides a filling opening through which may be projected a nozzle for waxing the interior of the container. After the container has been waxed, it is disposed in an inverted position and the hinged closure flap 52 and its attached plug 67 are held open for a time sufficient to permit the excess hot wax to drain from the interior of the container through the filling port 66.

A certain amount of the draining hot wax will run onto the outwardly or downwardly directed, generally circular area surrounding the port 66 on the inner ply of the top closure. When the draining period has been completed, closing the flap 52 brings it into contact with the residual wax on the marginal area surrounding the filler port 66, and as the wax cools to the solid state, it serves to seal the filling port and retain the closure flap 52 in its closed position. It will be apparent that the dispensing port closure plug 64 is firmly held in the port by the imperforate portions 60, 63 during this waxing of the interior of the carton, and hence virtually none of the wax will find its way into the space between the lower or inner top closure ply and the overlying tear strip portion defined between the lines of perforations 45 to cause adhesion of the tear strip to said ply or to body portions contacted by said strip.

The carton is now ready for filling with milk or other liquid product, which is usually done at a different location. Prior to this filling, heat may be applied to the closure flap 52 to soften the wax and release the flap. The flap 52 is then opened, and a nozzle is projected through the port 66 to effect the desired filling. After the filling has been completed, the closure flap 52 is again closed and reheated to soften the wax so that it may again act to seal the flap 52 in closed position.

In order to open a filled container, a customer grasps the finger grip extension 43 and pulls it upwardly thereby tearing the strip along the lines of perforations 45 so that as the tear strip is swung upwardly about the double score line hinge 44, the adhered dispensing port closure plug 64 will be forcibly extracted from the dispensing port 59 to expose the latter and permit out-pouring of milk therethrough. If only a portion of the milk is removed from the carton at a given pouring, it may be desirable to reclose the dispensing port to protect the portions over which the milk is poured from exposure to contamination. This may be accomplished by returning the tear strip to the position it occupied before it was separated or torn out from the outside ply of the top closure assembly. In this replacement of the tear strip the same is returned to overlie the portion of the dispensing port defined by the angularly disposed slits 61.

and the portion of the lower ply of the top closure overlying the adjacent outwardly directed supporting flange of the body. The tear strip will also be folded under the outwardly directed body flange in the manner illustrated in Figures 3 and 10, and the angled edge portions 50 thereof may be interlocked behind the complementary angled edges 49 on the free flap extensions 48 disposed at either side of the tear strip and overlying the adjacent upwardly and inwardly inclined wall portion 20 of the body wall 11 as shown in said figures, to effectively retain the tear strip reclosure in the closed position. It will be apparent that with the tear strip panel portion 40 folded under the body flange, there will be a tendency for the tear strip to straighten out and thereby force the angular edge portions 49 thereof downwardly into frictional contact with the like angled edges 50 on the reclosure flap retainers 48 as in the original position shown in Figure 1, or into locking position slightly behind said edges 50 as shown in Figure 3. In either case, the tear strip will be retained in its dispensing port closing and flange covering reclosure position.

Should a simple imperforate top closure of the forms shown in Figures 12 and 13 be employed, the carton is preferably filled before the top is applied and the carton is opened for dispensing the contents by tearing away all or a portion of said closure.

A closure of the nature of that shown in Figure 14 could be covered with the overcap 84 readily removable by manipulation of the free, extended finger piece 89. This overcap could be secured by a permanent adhesive, or a pressure sensitive adhesive permitting removal and reapplication of the closure cap could be employed. After removal of the overcap, by tearing away, or by complete removal thereof, the ports in the underlying closure would be exposed and the closures therefor could be removed in any approved manner.

While example forms of the invention have been shown for purposes of illustration, it is to be clearly understood that various changes in the details of construction and arrangement of parts herein disclosed may be made without departing from the spirit and scope of the invention as defined in the appended claims.

I claim:

1. In a carton of the character described, a tubular body formed of a regular rectangular sheet of paper devoid of slits or cut outs to include four connected side walls each having an outwardly turned flange at an end extremity thereof and a wall portion inclined inwardly toward juncture with the respective flange and effective to provide a finger grip clearance beneath the respective flange, outwardly projecting upright reinforcing rib means at each corner connection of adjacent side walls and serving to integrally connect the flanges and the inwardly inclined wall portions with the flanges in coplanar relation, each said rib means including a portion extending away from its integral juncture with two adjacent flanges in a plane perpendicular to the plane of the flanges, and a closure supported on and secured to said flanges.

2. In a carton of the character described, a tubular body formed of a regular rectangular sheet of paper devoid of slits or cut outs to include four connected side walls each having an outwardly turned flange at an end extremity thereof and a wall portion inclined inwardly toward juncture with the respective flange and effective to provide a finger grip clearance beneath the respective flange, outwardly projecting upright reinforcing rib means at each corner connection of adjacent side walls and serving to integrally connect the flanges and the inwardly inclined wall portions with the flanges in coplanar relation, each said rib means including a portion extending away from its integral juncture with two adjacent flanges in a plane perpendicular to the plane of the flanges and composed of integral portions of said two adjacent flanges folded downwardly and outwardly from said adjacent flanges and adhered together in face to face contact, and a closure supported on and secured to said flanges.

from said adjacent flanges and adhered together in face to face contact, and a closure supported on and secured to said flanges.

3. In a carton of the character described, a tubular body formed of a regular rectangular sheet of paper devoid of slits or cut outs to include four connected side walls each having an outwardly turned flange at an end extremity thereof and a wall portion inclined inwardly toward juncture with the respective flange and effective to provide a finger grip clearance beneath the respective flange, outwardly projecting upright reinforcing rib means at each corner connection of adjacent side walls and serving to integrally connect the flanges and the inwardly inclined wall portions with the flanges in coplanar relation, each said rib means including a portion extending away from its integral juncture with two adjacent flanges in a plane perpendicular to the plane of the flanges, a second portion coplanar with one of a pair of adjacent inclined wall portions and connecting said pair of adjacent inclined wall portions, and an angularly offset portion connecting said first mentioned and second portions, and a closure supported on and secured to said flanges.

4. In a carton of the character described, a tubular body formed of a regular rectangular sheet of paper devoid of slits or cut outs to include four connected side walls each having an outwardly turned flange at an end extremity thereof, a vertical wall portion integral with the flange and depending therefrom to provide a finger grip clearance therebeneath, and an upwardly and inwardly inclined wall portion connecting with said vertical wall portion, upright outwardly projecting rib means at each corner connection of adjacent side walls and serving to integrally connect the flanges and the inwardly inclined and vertical wall portions with the flanges in coplanar relation, each said rib means including a portion extending away from its integral juncture with two adjacent flanges in a plane perpendicular to the plane of the flanges, and a closure supported on and secured to said flanges.

5. In a carton of the character described, a tubular body formed of a regular rectangular sheet of paper devoid of slits or cut outs to include four connected side walls each having an outwardly turned flange at an end extremity thereof, a vertical wall portion integral with the flange and depending therefrom to provide a finger grip clearance therebeneath, and an upwardly and inwardly inclined wall portion connecting with said vertical wall portion, upright outwardly projecting rib means at each corner connection of adjacent side walls and serving to integrally connect the flanges and the inwardly inclined and vertical wall portions with the flanges in coplanar relation, each said rib means including a portion extending away from its integral juncture with two adjacent flanges in a plane perpendicular to the plane of the flanges and composed of integral portions of said two adjacent flanges folded downwardly and outwardly from said adjacent flanges and adhered together in face to face contact, and a closure supported on and secured to said flanges.

6. In a carton of the character described, a tubular body formed of a regular rectangular sheet of paper devoid of slits or cut outs to include four connected side walls each having an outwardly turned flange at an end extremity thereof, a vertical wall portion integral with the flange and depending therefrom to provide a finger grip clearance therebeneath, and an upwardly and inwardly inclined wall portion connecting with said vertical wall portion, upright outwardly projecting rib means at each corner connection of adjacent side walls and serving to integrally connect the flanges and the inwardly inclined and vertical wall portions with the flanges in coplanar relation, each said rib means including a portion extending away from its integral juncture with two adjacent flanges in a plane perpendicular to the plane

of the flanges and composed of integral portions of said two adjacent flanges folded downwardly and outwardly from said adjacent flanges and adhered together in face to face contact; a second portion coplanar with one of a pair of adjacent inclined wall portions and connecting said pair of adjacent inclined wall portions, and an angularly offset portion connecting said first mentioned and second rib portions and including integral parts connecting adjacent vertical wall portions and folded into angular position and face to face contact, and a closure supported on and secured to said flanges.

7. In a carton of the character described, a tubular body formed of a regular rectangular sheet of paper devoid of slits or cut outs to include four connected side walls each having an outwardly turned flange at an end extremity thereof, a vertical wall portion integral with the flange and depending therefrom to provide a finger grip clearance therebeneath, and an upwardly and inwardly inclined wall portion connecting with said vertical wall portion, upright outwardly projecting rib means at each corner connection of adjacent side walls and serving to integrally connect the flanges and the inwardly inclined and vertical wall portions with the flanges in coplanar relation, each said rib means including a portion extending away from its integral juncture with two adjacent flanges in a plane perpendicular to the plane of the flanges and composed of integral portions of said two adjacent flanges folded downwardly and outwardly from said adjacent flanges and adhered together in face to face contact, a second portion coplanar with one of a pair of adjacent inclined wall portions and connecting said pair of adjacent inclined wall portions, and an angularly offset portion connecting said first mentioned and second rib portions and including integral parts connecting adjacent vertical wall portions and folded into angular position and face to face contact and other parts of said pair of adjacent vertical wall portions folded into face to face contact in the plane of one of said pair of adjacent vertical wall portions and perpendicular and in right angular relation to the other of said pair of adjacent vertical wall portions, and a closure supported on and secured to said flanges.

8. A carton blank for a tubular carton of regular rectangular cross section having a flat flange at one end on which to receive an end closure, said blank comprising a rectangular paper sheet devoid of slits or cut outs and having four score lines traversing the full width of the blank in parallel spaced relation and defining between pairs thereof three connected wall panels and two half wall panels at the ends thereof adapted when the blank is folded as a tube and connected at its ends in a seam to compositely form a fourth wall panel, first, second and third longitudinal score lines extending full length of the blank and paralleling each other and the adjacent blank edge and intersecting said four score lines, said first score line with the adjacent blank edge defining a flange area at the position of each wall panel and half panel, said first and second score lines defining between them a vertical wall portion at the position of each wall panel and half panel, and said second and third score lines defining between them an inclined wall portion at the position of each wall panel and half panel, there being two connected triangular areas defined in the flange area and at the location where each of the four traversing score lines traverses the same by the respective traversing score line the first score line and two angled and converging score lines traversing the flange area and intersecting where the traversing score passes through the blank edge, two connected triangular areas defined in the vertical wall portion and at the location where each of the four traversing

score lines traverses the same by the respective traversing score the first score line and two angled and converging score lines traversing the vertical wall portion and connecting at one end with said angled score lines and intersecting at their other ends where the respective traversing score line intersects the second score line, two pairs of connected triangular areas formed in part in the central one of the three connected wall panels and one pair of connected triangular areas in each of the half wall panels, one triangular area of each said pair being defined in the area between the first and second score lines by one of the angled and converging score lines traversing said area the second score line and a score line traversing said area perpendicularly from the point of intersection of said one angled score line with the first score line and the other triangular area of each said pair being defined in the area between the second and third score lines by the respective traversing score line the second score line and a score line angularly traversing said area from the point of intersection of the third score line with the respective traversing score line to a point along the second score line where it joins with the line perpendicularly traversing the area between the first and second score lines.

9. A flat top paper milk carton comprising a tubular body formed from a regular rectangular body blank, said body blank being folded to provide side walls and outwardly extending flanges at ends thereof and integral throughout their full width with the side walls, said side walls being folded at the corners to provide double fold miter joints at the ends of the flanges to position the flanges in a common plane and in single thickness throughout the full length of each thereof, a top panel attached to the flanges, and a bottom panel secured to the other end of the body.

10. A flat top paper milk carton comprising a tubular body formed from a regular rectangular body blank, said body blank being folded for providing side walls and outwardly extending flanges at ends thereof and integral throughout their full width with the side walls, triangular corner folds at the ends of the flanges and integral with the flanges throughout the full width thereof and providing mitered joints and positioning the flanges in a common plane and in single thickness throughout the full length of each thereof, a top panel attached to the flanges, and a bottom panel secured to the other end of the body.

11. A flat top paper milk carton comprising a tubular body formed from a regular rectangular body blank, said body blank being folded for providing side walls and outwardly extending flanges at ends thereof and integral throughout their full width with the side walls, depending corner folds connecting the flanges and integral with the flanges throughout the full width thereof and providing double fold mitered joints therebetween, a top panel attached to the flanges, and a bottom panel secured to the other end of the body.
